RIBBON CUTTER

Herbert Platt, Cumberland, Md., assignor to Celanese Corporation of America, a corporation of Delaware

Application September 7, 1934, Serial No. 743,053

8 Claims.

(Cl. 18—1)

This invention relates to the method and device for cutting substantially continuous ribbons from a sheet of thermoplastic material and more particularly from a fabric containing organic derivatives of cellulose.

An object of the invention is the economic and expeditious method, and a device for performing same, of cutting substantially full width fabric containing organic derivatives of cellulose into narrow widths such as ribbons and forming a false selvedge by sealing the edges of the ribbons against fraying. Other objects of the invention will appear from the following detailed description.

15 In the drawings like numerals refer to the same or similar elements on the various figures.

Fig. 1 is an end elevation of a cutting device constructed in accordance with this invention.

Fig. 2 is a front view partially in section of a heated cutting element for use in a device as shown in Fig. 1.

Fig. 3 is a cross-sectional view taken on the line 3—3 of Fig. 2 of the heating element and cutter.

Fig. 4 is a plan view of a piece of fabric passing the cutting elements and shows the separation of the fabric at the rear of the cutting elements.

The cutting of fabric into a plurality of ribbons, heretofore, has not met with great commercial success in that no satisfactory means could be found to prevent the cut edges from fraying. With the advent of fabrics of organic derivatives of cellulose, however, it was found that the cut edges could be sealed against fraying by fusing the ends of the yarns together. It was also found that the cutting and sealing of the edges could be done simultaneously by cutting such a fabric with a hot knife. However, the cutting of a plurality of ribbons from a sheet of fabric presents many serious difficulties.

In cutting ribbons from a fabric, especially if the knives are relatively close together, the ribbons are fused along the frayed edge such that upon contact with another fused edge or even the fabric of another ribbon or another part of the same ribbon a welding action takes place, tacking the material together in an unusable condition. This is accentuated when the heated cutting knives are closely spaced, say $\frac{1}{2}$ to 2 inches as the heat necessarily radiated from the knives effects more or less the entire width of the ribbon. By my invention, however, this rejoining of the cut fabric is prevented and also any injurious effect of radiated heat on the uncut part of the fabric is reduced to a minimum. The fabric is

cut unsupported by metallic or other solid surfaces and the cut edges are held separated from each other and also from the device until they have cooled to below a tacky temperature.

By employing my invention, ribbons of very narrow widths, say less than $\frac{1}{2}$ inch, as well as wide widths may be cut from fabric containing a thermoplastic derivative of cellulose such as fabric woven, knitted or otherwise formed from yarns at least some of which contain organic derivatives of cellulose such as the organic esters of cellulose and cellulose ethers. Examples of organic esters of cellulose are cellulose acetate, cellulose formate, cellulose propionate and cellulose butyrate, while examples of cellulose ethers are ethyl cellulose, methyl cellulose and benzyl cellulose.

According to my invention, then, I cut fabrics at least some of the yarns of which contain filaments of thermoplastic derivatives of cellulose into ribbons or other shapes with a heated cutting element such that the cut filaments of thermoplastic derivatives of cellulose are fused and prevented from fraying and maintaining the fused portion isolated from other parts of the fabric until the thermoplastic material has cooled to a point of non-tackiness. The cooling may be hastened by drawing the heat from the material by means of a heat absorbing element and thus the time required for maintaining the cut edges isolated is materially shortened. The tacky fused edges are also isolated from any solid elements of the device. This may be accomplished by cutting the fabric at a point suspended between two spaced supports.

This invention although described in detail in reference to the formation of ribbons is also applicable to dividing, parting, trimming or perforating fabrics. The fabric may be formed entirely of filaments containing organic derivatives of cellulose or it may be formed such that other filaments and/or fibres are present. Thus alternate warp, weft or both warp and weft yarns may contain a thermoplastic derivative of cellulose and the other alternate yarns may be cotton, regenerated or reconstituted cellulose, silk, flax or the like. Further, only the weft yarns need contain thermoplastic derivatives of cellulose. Also the individual yarns may contain a mixture of a thermoplastic derivative of cellulose filaments and filaments or fibres of other materials. Obviously any combination or arrangement of fibres and filaments may be employed with the degree of sealing or forming of a false selvedge.

at the cut being proportional to the amount of thermoplastic filaments there present.

The filaments containing thermoplastic derivatives of cellulose and/or other artificial or natural fibres and filaments may contain effect materials for adding color, stiffness, pliability, hand, and other effects and agents to regulate the melting point of the material. For example, the yarns or filaments may contain dyes, lakes, fire retardants, sizes, filler, lubricants, pigments and/or plasticizers. Although any suitable plasticizer may be employed there are some that can be selected for their melting point and also the point at which they become solvents for the organic derivatives of cellulose such that when incorporated with the fabric they lower the temperature of fusion and thus the required temperature of the cutting elements. Such plasticizers are, for example, diacetone alcohol, diethyl tartrate, di-20 methyl phthalate, cyclohexanone, etc. These plasticizers may be incorporated in the filaments at the formation of the filaments or at any subsequent period or they may be padded or sprayed upon the fabric just prior to cutting.

25 As an example of an industrial application of the invention to the formation of ribbons, a length or piece of woven fabric (and especially a fabric made wholly of threads or yarns of cellulose acetate or other cellulose ester or ether) with or 30 without a treatment of plasticizer, may be divided or parted into any number of widths, strips, ribbons or pieces by drawing or passing the fabric in contact with one or more knives, blades or other like cutting elements heated to the required 35 temperature, whereby the cellulose ester or ether yarns are melted along the line or lines of contact with the knife or knives, blade, or blades or the like and by means of the shape of the cutting element or an attachment immediately behind the 40 cutting element or the arrangement of the drawing device the melted edge or edges are held isolated until solidified; the heated surface or surfaces seals the edges by melting the threads, at the same time cementing them together. This 45 constitutes a simple form of binding the edges of the pieces preventing fraying and, by reason of the slight bead formed, making more strong its resistance to tearing.

Alternatively the heated cutting element or 50 elements may be drawn across the stationary or moving fabric. The dividing or parting may be performed in any direction of the fabric, for instance, longitudinally or transversely, or both longitudinally and transversely.

55 If a number of suitably disposed knives are employed, a number of bands, strips or ribbons may be severed simultaneously. The binding formed by the fusion of the filaments or threads during the dividing or parting of the fabrics may 60 replace selvedges in the resulting bands, strips, ribbons or pieces of fabric. The sealing of the edges by the heat as referred to in the case of ribbons and the like constitutes a marked advantage over ribbons, etc., with glued edges, in that 65 no deterioration of the ribbon, etc., takes place when the edge sealed by heat gets wet.

As another example of the application of the invention, it may be applied to the production of woven labels, tabs or the like by severing them 70 from a suitable fabric. For example, a fabric may be woven from threads of cellulose acetate (or other cellulose ester or ether) with a number of repeats of the label or tab across the width (for instance 20 repeats), the lettering or design of 75 the label or tab being formed from similar or dis-

similar threads to that of the fabric, or a label may be printed on the fabric. With or without first treating the fabric with a plasticizer, the labels may then be severed entirely or in strips of repeating labels, by lines longitudinally and/or transversely, from the fabric with a heated knife or knives, blade or blades or the like while retaining the freshly cut edges isolated until cooled.

Obviously many other applications of the invention may be made by modifying the cutting 10 device and arrangement of cutter, heating and cooling units.

In the drawings there is disclosed one form of a device for carrying out this invention, that is also a part of my invention. This device is constructed for the cutting of ribbons or strips of narrow width longitudinally from a fabric.

In the drawings with particular reference to Fig. 1 which shows an end view of a device 1 is a frame having mounted thereon brackets 2 and 3 supporting track rails 4 and 5 respectively. Mounted for movement on the track rails is a carriage 6 supported on the rails by wheels 7 and 8. On upwardly extending arms 9 of the carriage 6 are holders 10 for supporting the ends of a shaft 11 about which may be wound a length of fabric 12. By movement of the carriage 6 the feed of the fabric may be adjusted relative to the remaining part of the device.

Suitably mounted on the frame 1 is a bracket 13 supporting a motor 14 or other source of power preferably having a variable speed. From the source of power a belt 15 drives a pulley 16 mounted on a shaft 17 suitably journaled in the main frame 1 by means of bearings 18. On the shaft 17 is a clutch mechanism 19 that may consist of two pulleys one positive to the shaft and the other an idler such that a belt 20 may be shifted as desired from the driven pulley to the idler pulley.

A shaft 21 pivoted in the main frame 1 in bearings 22, has fastened thereto a clutch shifting member 23 that moves belt 20 or other clutch mechanism to govern the position of belt 20. The shaft 21 may be rotated from either side of the 40 device by means of handles 24 and 25 fastened thereto.

The belt 20 drives a pulley 26 fastened to a shaft 27 that has mounted thereon a friction drum 28. The friction drum may be solid or hollow and formed of any suitable material. It is preferably covered with cork or other composition for insuring a positive drive of a roll 29 of ribbons cut from the fabric 12. The roll 29 may consist of a shaft 30 carrying a roll 31 about which the 55 ribbons are wrapped. The roll is guided and held in contact with the friction drum 28 by means of guides 32 operating on the ends of the shaft 30 and contained in an arm 33 pivotally connected to a carriage 34.

A carriage 34 adapted for sliding movement in a substantially vertical direction in uprights 36 of the main frame 1 has mounted thereon two shafts 37 and 38. Each shaft 37 and 38 carries guide roll 39 and 40 respectively. Also mounted in the carriage 34 is a tensioning device 41 for maintaining an even and regulatable tension on the fabric. By means of a lever 42 pivoted on shaft 43 that carries a cam or other suitable member this carriage 34 may be vertically adjusted and held in position relative to the main frame 36 that has stationarily mounted thereon a heating and cutting device 44. The carriage 34 also carries two supporting bars 45 and 46. Bar 45 may be of any polished surface while bar 75

- 46 is preferably hollow and made of metal with means for circulating a cooling fluid such as water through the interior thereof. The space between the supporting bar in front of the knife 5 and the water or other liquid cooler behind the knife may be filled in with asbestos powder or the like so that the blades, when cutting, dip down or partially dip down into a cushion of asbestos instead of a cool air pocket.
- 10 The heated cutting or dividing element may be fastened to the uprights 36 of the main frame by a cross-piece or plurality of brackets 44. The cutting element preferably comprises an electric coil or resistance rod 47 contained in a metallic conductor tube 48 that has connected thereto a flattened surface or otherwise a blade holder 49. The blade holder 49 may consist of two spaced bars 50 and 51 or a slotted bar that is held in heat transfer relation to the heated conductor tube as by means of screws 52 and 53. Fastened to or otherwise suitably held in contact with the conductor tube are thermocouples or other suitable temperature measuring devices 54.
- 20 Blades 55 may be suitably spaced in the blade holder 49 and positively fastened thereto by means of set screws 56. Thus, blade holder rods with blades set at any desired spacing may be readily attached to a conductor tube. The heating element, conductor tube and blade supporting bars should preferably be massive enough to maintain a comparatively large reserve of heat so that the temperature of the blades is not lowered upon their contact with the fabric. The metals or metal alloys employed should preferably be good conductors of heat, such as copper, steel, tungsten, etc.
- 25 The conductor tube 48 may be supported somewhat centrally of a larger tube 57 having a sector thereof removed as at 58 through which the cutting blades 55 are adapted to project. The conductor tube 48 is held properly positioned in the larger tube 57 by means of spaced positioning screws 59 operating in threaded taps in the larger tube. The space between the conductor tube 48 and the larger tube 57 may be filled with a heat insulating material 60, such as asbestos fibre, that is supported in blade-holder covering position by means of a wire mesh or screen 61.
- 30 The larger or outer tube 57 may be suitably fastened to the main frame through bar or brackets 44 by attaching same to an angle bar 62 by means of bolts 63 suitably spaced along its length. The angle bar 62 preferably has positioned therein holes 64 that register with and permit the adjustment of positioning screws 59.
- 35 Either the outer tube 57, the conductor tube 48 or the heating element 47 may be made in sections or all may be made in registering sections or staggering sections such that the joint 40 of one does not fall in line with the joint of another. The heating element 47 may be formed with push plug prongs 65 for connecting to a source of electricity or into each other. In place of an electrical resistance coil or rod, other heating means may be employed. However, the fine degree of heat control and compactness of electrical heating elements make them most desirable.
- 45 The blade 55 preferably consists of a square shank 66 adapted for heat exchange contact with blade holder 49 and conductor tube 48 and is of such a weight as to contain a fair reserve of heat. The forward edge 67 of the blade is brought to a knife edge while the rear 68 of the blade is comparatively wide, thus forming a
- blade that in cross-section is triangular. The rear of the blade preferably is shorter than the front. This shape of blade not only cuts and/or melts the fabric being treated but also curls the cut edges upward such that they do not contact with other edges or the fabric for a space back of the blade which permits the cooling action of the cooling member 46 to solidify the fused edges before they contact with each other. The fabric is preferably not solidly supported at the point of cutting but is suspended between the elements 45 and 46.
- 50 In operation, a roll of fabric to be cut is placed on the holder 10 and the fabric threaded through the tensioning device 41 and over guide roller 39, supporting bar 45, cooling element 46, guide roller 40, about friction roller 28 and onto spool or take-up package 29. The fabric is thus stretched, uncontacted by the blades, across the line of engagement with the blades. This is done while the carriage 34 is in a lowered position and the fabric is out of contact with the heated blades. The fabric is then pulled onto the take-up package and the carriage 34 raised until the fabric is forced onto the blades which project down into the space between supporting bar 45 and cooling element 46. The short back of the blade prevents cooling of the blade by proximity to the cooling element. The cooling of the blade may be further prevented by filling the blade receiving pocket with asbestos. The fabric being pulled against the heated blades, that may be heated to a temperature of from 260° C. to 1200° C. or more, depending on the speed of cutting and the thermoplastic properties of the material, is cut and the cut ends of the thermoplastic filaments are fused by contact with the blades forming a false selvedge at the edges of the cut. The triangular shape of the blades holds the cut and fused edges of the fabric separated until they are cooled below tackiness by the cooling element that contacts therewith and permanently sets the fused material before the same reaches the guides or spool.
- 55 In cutting an all cellulose acetate fabric into $\frac{1}{8}$ inch ribbons, the knives may be heated to a red heat and the fabric run past the blades at a speed of from 10 to 20 yarns per minute. The edge and the bead obtained under these conditions are very good. The blades are preferably maintained at a high temperature and the fabric speed kept sufficiently high to prevent scorching to obtain the best edge and the cleanest bead. If sufficient speed is employed the blades may be maintained at temperatures far above the scorching temperature of the fabric.
- 60 The material of the blades may be copper, copper alloy, steel, other suitable metal alloys or ceramic material according to the strength desired in the cutting edge at the temperature employed.
- 65 It is to be understood that the foregoing detailed description and drawings are merely given by way of illustration and many alterations may be made therein without departing from the spirit of my invention.
- 70 Having described my invention, what I desire to secure by Letters Patent is:
1. Process for the production of ribbons from woven, knitted or other fabric containing yarns of a thermoplastic derivative of cellulose, which comprises severing the fabric with a cutting element, maintained at a temperature above the scorching temperature of the thermoplastic de-

5. In a device for severing thermoplastic sheet material, the combination with means for feeding a length of sheet material, of a cutting element and means for heating the same, the construction and arrangement of the cutting element being such that the back thereof is of substantial width so that the cut edges of the material are kept apart for a substantial distance behind the cutting edge of the cutting element.

5

6. Process for the production of ribbons from woven, knitted or other fabric containing yarns of cellulose acetate, which comprises severing

10 the fabric with a cutting element, maintained at a temperature above the scorching temperature of the cellulose acetate, by a relative movement between the fabric and the cutting element at a speed which prevents scorching of the fabric and positively cooling the cut edges of the fabric before allowing the same to contact with any portion of the fabric.

7. Process for the production of ribbons from woven, knitted or other fabric containing yarns

20 of a thermoplastic material, which comprises severing the fabric with a cutting element maintained at a temperature above the fusion temperature of the thermoplastic material and positively cooling the cut edges of the fabric before allowing the same to contact with any portion of the fabric.

8. Process for the production of ribbons from woven, knitted or other fabric containing yarns of cellulose acetate, which comprises severing the

25 fabric with a cutting element maintained at a temperature above the fusion temperature of the cellulose acetate and positively cooling the cut edges of the fabric before allowing the same to contact with any portion of the fabric.

10

9. In a device for severing thermoplastic sheet material, the combination with means for feeding a length of sheet material, of a cutting element and means for heating the same, said cutting

15 element being triangular in cross-section and having a back portion of substantial width, which back portion is adapted to keep apart the cut edges of the material for a substantial distance behind the cutting edge of the cutting element.

15

10. In a device for severing thermoplastic sheet material, the combination with a heated cutting element and means for feeding a length of sheet material relative to the heated cutting element, of means for cooling the cut material at a point immediately behind the cutting edge of the cutting element.

20

11. A device for severing thermoplastic sheet material comprising a cutting element, means for heating the same, and means for feeding a length of sheet material to the cutting element, said feeding means including a guide member adjacent to but out of contact with the cutting element and adapted to cool the cut material.

25
